DESIGN FOR A COAT

Jacob Judenfreund, New York, N. Y.

Application January 20, 1939, Serial No. 82,459

Term of patent 3½ years

To all whom it may concern:

Be it known that I, Jacob Judenfreund, a citizen of the United States of America, residing in New York city, in the Borough of Manhattan, county and State of New York, have invented a new, original, and ornamental Design for a Coat, of which the following is a specification, reference being had to the accompanying drawing, forming part thereof, wherein

Figure 1 is a front view of a coat showing my new design.

Figure 2 is a rear view of the coat shown in Figure 1.

The characteristic feature of my design resides in the combination on the coat disclosed of the diagonal flap pockets with connecting seams, in association with front and rear stitched panel seams which graduate into raised tucks on the skirt portion as shown.

I claim:

The ornamental design for a coat, substantially as shown and described.

JACOB JUDENFREUND.
